UNITED STATES PATENT OFFICE

154,627

DESIGN FOR A COMBINED FLASHLIGHT
AND TESTER

Frank Peterlin and John F. Peterlin, Joliet, Ill.

Application July 9, 1948, Serial No. 147,468

Term of patent 14 years

(Cl. D48—25)

To all whom it may concern:

Be it known that we, Frank Peterlin and John F. Peterlin, citizens of the United States, residing in Joliet, in the county of Will and the State of Illinois, have invented a new, original, and ornamental Design for a Combined Flashlight and Tester, of which the following is a specification, reference being had to the accompanying drawings, forming part thereof, in which:

Fig. 1 is a side elevational view of a combined flashlight and tester, showing our new design;

Fig. 2 is a front elevational view thereof; and
Fig. 3 is a bottom view of the same.

We claim:

The ornamental design for a combined flashlight and tester, substantially as shown.

FRANK PETERLIN.
JOHN F. PETERLIN.
